(57) **CLAIM**

The ornamental design for a rotatable vanity mirror, as shown and described.

DESCRIPTION

FIG. 1 is a left-side elevation view of a rotatable vanity mirror, showing my new design.

FIG. 2 is a front elevation view thereof.

FIG. 3 is a right-side elevation view thereof.

FIG. 4 is a top plan view thereof.

FIG. 5 is a bottom plan view thereof.

FIG. 6 is a rear elevation view thereof.

FIG. 7 is a perspective view thereof.

FIG. 8 is a front elevation view thereof with the mirror and light ring in an angled position.

FIG. 9 is a right-side elevation view thereof with the mirror and light ring in an angled position.

FIG. 10 is a perspective view thereof with the mirror and light ring in an angled position; and,

FIG. 11 is a perspective view thereof with the mirror and light ring in different angled positions.

The broken lines in the drawings represent portions of the rotatable vanity mirror that are for illustrative purposes only and do not form a part of the claimed design.

1 Claim, 10 Drawing Sheets
